UNITED STATES PATENT OFFICE.

EPPA H. RYON, OF WALTHAM, MASSACHUSETTS, ASSIGNEE TO CROMPTON & KNOWLES
LOOM WORKS, A CORPORATION OF MAINE.

PATTERN MECHANISM FOR LOOMS.

1,073,635.

Specification of Letters Patent. Patented Sept. 23, 1913.

Application filed March 10, 1913. Serial No. 753,166.

To all whom it may concern:

Be it known that I, EPPA H. RYON, a citizen of the United States, residing at Waltham, in the county of Middlesex and State of Massachusetts, have invented certain new and useful Improvements in Pattern Mechanism for Looms, of which the following is a specification.

My invention relates to a pattern mechanism for looms, and the object of my invention is to provide a pattern mechanism of improved construction, and particularly adapted to be used on looms for weaving pick and pick for a predetermined time, to 15 rock the box pattern chain cylinder back and forth, through the action of an oscillating pin wheel, which moves two bars of 20 the box pattern chain into action alternately, for the vibrator levers of the well known Knowles head motion.

In my improvements, I provide an oscillating segment gear which meshes with a toothed portion on a pin wheel, and causes the pin wheel to be rocked in one direction 25 for one pick and in the opposite direction for the other pick. Said pin wheel operates a star wheel, which is fast on a sleeve on the box pattern chain cylinder, which operates the vibrator levers in the usual way.

My invention consists in certain novel features of construction of my improvements as will be hereinafter fully described.

I have shown in the drawings my improvements combined with the well known 35 type of drop box pattern chain mechanism, and multiplier pattern chain mechanism, operated by pin wheels, and star wheels, shown and described in U. S. Letters Patent No. 413,369, dated October 22, 1889.

I have only shown in the drawings a detached portion of the drop box pattern chain mechanism, and the multiplier pattern chain mechanism, with my improvements combined therewith, sufficient to enable those 45 skilled in the art to understand the construction and operation thereof.

Referring to the drawings:—Figure 1 is a sectional front view of a box pattern chain mechanism, and a multiplier pattern chain mechanism, with my improvements applied thereto, said section taken at a point indicated by line 1, 1, Fig. 2, looking in the direction of arrow *a*, same figure. Fig. 2 is an end view of the parts shown in Fig. 1, 55 looking in the direction of arrow *b*, same

figure. Fig. 3 is a section, on line 3, 3, Fig. 1, looking in the direction of arrow *b*, same figure. Fig. 4 corresponds to Fig. 3, but shows some of the parts shown in Fig. 3, in a different position, and, Fig. 5 is a sectional view of the pin wheel mechanism, detached.

In the accompanying drawings, 1 is a portion of a loom head frame, on which is secured a stand 2, on which stand are supported the several parts of the pattern chain indicating mechanism.

3 is a shaft, suitably supported, which has a sleeve 4 mounted thereon, carrying the pattern chain cylinder 5, see Fig. 1, having 70 thereon the drop box pattern chain 6, made up of links and bars, said bars carrying rolls and tubes, in the ordinary way.

On the outer end of the shaft 3 is loosely mounted the pattern chain cylinder 8, see 75 Figs. 1 and 2, carrying the auxiliary multiplier pattern chain 9, made up of links and bars, said bars carrying rolls and tubes, in the ordinary way. Fast on the sleeve 8' on the multiplier pattern chain cylinder 8, is a 80 star wheel 10.

Extending over the box pattern chain 6 is an indicator lever 11, which is pivoted on a shaft 12, see Fig. 2, on the frame 1, and connected, through the connector 13, and 85 angle lever 14, pivoted at 15 on a stationary rod 16, with a collar 17 on a longitudinally sliding rod 18, see Fig. 1. The outer end of the sliding rod 18 has a yoke shaped arm 19 fast thereon, which engages a pin wheel 90 20, splined on a rotary driven sleeve 21, having the gear 21' thereon, which sleeve is loosely mounted on a stationary shaft 22, see Fig. 5. The pin wheel 20 is adapted to 95 be moved into and out of engagement with the star wheel 10 of the auxiliary pattern chain cylinder 8, through the indication of the box pattern chain 6.

A spring 23, see Fig. 1, secured to an extension 14' on an angle lever 14, and to a 100 stationary part of the frame, acts to move the angle lever 14 and the rod 18, and carry the pin wheel 20 out of engagement with the star wheel 10. Pivotedly mounted on a 105 stand 24, secured to the frame 2, is an indicator lever 25, see Fig. 2, which extends over the multiplier pattern chain 9, and which is connected, through a connector 26 and an angle lever 27, pivoted at 28 on the stationary rod 16, with a collar 29 fast on a 110

longitudinally sliding rod 30, see Fig. 1. The sliding rod 30 has fast thereon the two yoke shaped arms 31 and 32, which are adapted to engage and hold in place on the sleeve 21 the two pin wheels 33 and 34. The pin wheel 33 is splined on the driven rotary sleeve 21, see Fig. 5, and is adapted to move into and out of engagement with the star wheel 7 of the box pattern chain cylinder 5, see Fig. 1. A spring 35 is attached at one end to an extension 27' on an angle lever 27, and to a stationary part of the frame 2, and acts to move the angle lever 27 and the sliding rod 30, and carry the pin wheel 33 out of engagement with the star wheel 7.

The shaft 36, see Fig. 1, which is driven from the chain shaft gear, not shown, in the usual way, on its opposite end, has mounted thereon, the pinion 37, see Fig. 2, which meshes with and drives the gear 21' on the revolving sleeve 21, to operate the pin wheels 20 and 33, which in this instance make a complete revolution every two picks. The pin wheels 20 and 23 are provided with two arms, carrying pins 20' and 23', respectively, to operate the star wheels 10 and 7, see Fig. 1.

All of the above mentioned parts, except the pin wheel 34, may be of the usual and well known construction, and operated in the usual and well known way.

I will now describe my improvements, which as above stated, consist of means for rocking the box pattern chain cylinder back and forth for a predetermined time.

The pinion 37 on the shaft 36 also meshes with and drives a gear 38, see Fig. 2, which in this instance is loosely mounted on a stud 39 on the frame 2. The gear 38 has a crank pin 40 thereon, to which is pivotally connected one end of the connector 41; the other end of the connector 41 is pivotally connected to a stud 42 on the oscillating gear 43. The oscillating gear 43, in this instance a segment gear, has its hub 43' loosely mounted on the stud 44 on the frame 2. The revolving of the gear 38 causes the segment gear 43, through the connector 41, to oscillate the pin wheel 34, which in this instance is loosely mounted on the sleeve 21, and has the toothed portion 34', see Fig. 5, thereon, which meshes with the teeth on the segment gear 43, which causes the pin wheel 34 to be rocked, in one direction for one pick, and in the opposite direction for the other pick, see Fig. 4. When there is no roll on the multiplier pattern chain 9 under the indicator lever 25, the pin wheels 33 and 34 are caused to slide to the left in

Fig. 1, through the action of the spring 35, and the oscillating pin wheel 34 is moved into engagement with the star wheel 7, which is fast on the sleeve 4 of the box

pattern chain cylinder 5. The pin wheel 34 causes the pattern chain cylinder 5 to rock back and forth, and bring two contiguous bars of the box pattern chain 6 into action alternately, under the vibrator levers, not shown. When a roll of the multiplier pattern chain 9 moves under the lever 25, the pin wheels 33 and 34 are caused to slide to the right in Fig. 1, and the pin wheel 33 is moved into engagement with the star wheel 7, and the box pattern chain 6 is caused to move forward every pick in the same direction, as long as a roll on the multiplier pattern chain 9 is under the lever 25.

Instead of having a double pin wheel 20, which operates the multiplier pattern chain cylinder 8 every pick, a single pin wheel 80 may be employed, which in this instance will advance the multiplier pattern chain 9 one bar for every two picks, and two different kinds of filling may be interwoven by each bar of the multiplier pattern chain. 85

It will be understood that the details of construction of my improvements may be varied if desired.

Having thus described my invention, what I claim as new and desire to secure by Letters Patent is:

1. In a pattern mechanism for looms, pattern surfaces, a star wheel connected therewith, two pin wheels to operate said star wheel, means to rotate one of said pin wheels continuously in one direction, and means to oscillate the other pin wheel, and means to move either of said pin wheels, to operate said star wheel. 95

2. In a pattern mechanism for looms, pattern surfaces, a star wheel connected therewith, two pin wheels to operate said star wheel, means to rotate one of said pin wheels continuously in one direction, and means to oscillate the other pin wheel, said oscillating means including teeth on the last mentioned pin wheel, said teeth meshing with and driven by an oscillating gear, and said oscillating gear. 100

3. In a pattern mechanism for looms, pattern surfaces, a star wheel connected therewith, two pin wheels to operate said star wheel, means to operate one of said pin wheels continuously in one direction, and means to oscillate the other pin wheel, said means including a driven gear, a crank thereon, a connector to a second gear, to oscillate said second gear, and said second gear, meshing with and driving said oscillating pin wheel, and means to move either 115 of said pin wheels, to operate said star wheel. 120
